UNITED STATES PATENT OFFICE.

DINO SAMAIA, OF MILAN, ITALY.

AUTOMATIC BLOCK APPARATUS FOR ELECTRIC TRAMWAYS AND RAILWAYS.

1,424,217.

Specification of Letters Patent. Patented Aug. 1, 1922.

Application filed December 30, 1919. Serial No. 348,426.

To all whom it may concern:

Be it known that I, DINO SAMAIA, a subject of the King of Italy, residing at No. 57 Foro Bonaparte, Milan, Italy, have invented 5 certain new and useful Improvements in Automatic Block Apparatus for Electric Tramways and Railways, of which the following is a specification.

This invention has for its object to provide 10 an improved block apparatus for electric tramways and railways.

The improved apparatus is so designed that the entry of one or more vehicles into a given section will bring into operation a 15 numbering device that will signal the number of vehicles that have entered the said section, said device being returned into its initial position or position of rest only when an equal number of vehicles has left the said 20 section.

As shown in the accompanying drawing which illustrates by way of example an embodiment of this invention:—

The improved apparatus comprises a solenoid 1 whose core is excited each time a vehicle enters the section, and a solenoid 2 whose core is excited each time a vehicle leaves the said section. The core 3 of each of the said solenoids is connected at its inner 25 end to a spiral spring 4, whereas its outer end is engaged by means of a stud 5 with a buttonhole slot 6 formed in one of the ends of a rocking beam 7. The opposite end of this rocking beam which has the form of a 30 fork 8, engages with a stud 9 fixed to a rack 10 having ratchet teeth.

Between the two racks there is arranged so as to slide in a guide 11, a support 12 carrying a pin 13 on which is mounted a 40 ratchet toothed wheel 15 meshing with the racks 10; the rotation of this wheel is controlled by a pawl 16.

17 are spring stops or buffers serving to keep the racks 10 applied elastically with 45 their teeth against the teeth of the wheel 15.

A rod 18 adapted to slide in a guide, abuts with its inner end against the head of the support 12, its outer end being pivoted to a lever 19 that is controlled by a spring stop 50 or buffer 20. This lever 19 with its carbon contact A and opposing contact B, acts as an interrupter in the blocking and unblocking signalling circuit, as well as for the circuit of a series of progressively numbered lamps 55 21. The contact block A is connected to the

current conductor C while the contact B is connected to the signalling line or circuit D. The lamps 21 are not illustrated in detail in the drawing as they may be of any appropriate type, and it will be understood that 60 these lamps and the attachments therefor are indicated jointly by the numeral 21. The lamps are numbered progressively in the same manner as the contacts by which their lighting is controlled, thus to the contact 23 65 identified by the numeral 1 will correspond a lamp numbered 1, to the contact numbered 2 a lamp numbered 2 and so on.

To distribute the current to the said lamps 21 (as soon as the lever 19 closes the circuit), 70 there is provided a distributing ring 22 which has upon its annular surface contacts 23 corresponding to the numbered lamps 21. Concentrically to the ring 22 there is mounted upon a pin 24 a toothed wheel 25 75 (indicated by a dotted circle in the drawing) carrying a pointer 26 pivotally mounted on the same center as the toothed wheel 25 and designed to close the circuit through the contacts 23. The wheel 25 is actuated by a pitch 80 chain 27 passing over rollers 28 and 29. This chain is fixed at one of its points to the sliding support 12. The pointer 26 is electrically connected to the earth as indicated at E so that every time the pointer bears against one 85 of the contacts 23 of the distributing ring, the corresponding lamp 21 will be lighted.

The operation of the improved apparatus is as follows:—

When, on the entry of a vehicle on to the 90 section, the block solenoid 1 is excited, the attraction of its core 3 has the result of actuating the rocking beam 7 by means of the stud 5 engaged in the slot 6. The forked end 8 of the rocking beam 7 acts in its turn upon 95 the rack 10, causing the latter to move to the left one tooth, which is possible owing to the toothed wheel 15 not being moved, due to the elasticity of the stops 17 and the peculiar shape of the teeth of the rack.

As soon as the solenoid has ceased to be 100 excited, the spiral spring 4 pushes back the core 3, thus returning the rocking beam 7 and the rack 10 into their original positions. The rack 10 is thus brought again from left 105 towards the right acting by means of its teeth upon the toothed wheel 15 which is caused to turn about its pivot 13 and at the same time to ride upon the teeth of the opposite rack 10, since this latter does not move 110

owing to the fact that the pressure exerted by the wheel 15 is such as not to overcome the pressure of the elastic stops 17. The result is that as the pivot 13 of the toothed wheel 15 is fixed to the sliding support 12, the latter is also shifted towards the right. In consequence of this movement of the support 12, the rod 18 with interrupter 19 is moved under the action of the spring stop 20. The contacts A and B thereby close the signalling circuit and also the circuit of the lamps 21. At the same time the action exerted upon the pitch chain 27 by the movement of the support 12 has the result of causing the wheel 25 to rotate, and causing the pointer 26 to close the circuit through the contact corresponding to the first lamp of the series of lamps 21. It is obvious that on the entry of a second vehicle on to the section, the same actions will be repeated and the circuit will be closed through the second lamp of the series, and so on.

For de-blocking, the operations are the same but in reversed order as for blocking, 25 until the support 12 again presses against the rod 18 and causes the lever 19 with contact A to move away from contact B, and consequently effect the interruption of the circuit. In operation, if for instance, five 30 cars have entered the section and the wheel 15 together with the support 12 have been moved by the distance of five teeth of the rack 10 on the block side and the pointer 26 has in consequence been successively brought 35 from the contact 1 corresponding to the lamp 1 to the contact 5 corresponding to the lamp 5, then the said five cars leave the section which will result that wheel 15 together with the support 12 will be moved for the distance 40 of five teeth of the rack 10 and consequently the pointer 26 will be returned from the contact 5 to its initial zero position. Evidently when the support 12 bears against the rod 18 the contact A of the lever 19 is moved 45 away from the contact D and the signalling circuit is interrupted.

It is to be noted that in the case of a simultaneous excitation of the two solenoids 1 and 2, that is to say, where a vehicle should happen to enter the section at the same instant that another vehicle is leaving the said section, the wheel 15 will revolve on its own axis without affecting the support 12 and consequently without producing any signalling.

The rocking beams 7 each comprise a nose 30 which projects into a slot in the core 3. This nose is designed to move the contact 31 that also projects into the said slot away 35 each time the core of the respective solenoid has been sucked in. This has the result of inserting a resistance into the circuit of the solenoid for the purpose of preventing an

excessive heating in the case of a too prolonged excitation.

The improved block apparatus is described hereinabove in its application to a system of light signalling, but it is obvious that it is applicable likewise to all signalling systems.

What I claim is:—

1. In automatic block apparatus for electric tramways and railways, the combination of a blocking solenoid, whereof the core is attracted each time a vehicle enters the block section, a de-blocking solenoid whereof the core is attracted each time a vehicle leaves said block section, a toothed wheel, racks meshing with said toothed wheel, rocking beams acting upon said racks, connections between said cores and said rocking beams, a support carrying said toothed wheel, slideable between said racks, a series of progressively numbered electric lamps, circuits supplying current to said lamps, a distributor controlling the supply circuits of said lamps, and means for energizing said solenoids, whereby each time a vehicle enters or leaves said block section, said support is actuated by the corresponding solenoid core to operate said distributor in such a manner as to light up or extinguish the lamp showing the number of the vehicles in said block section.

2. In automatic block apparatus for electric tramways and railways, the combination of a blocking solenoid, whereof the core is attracted each time a vehicle enters the block section, a de-blocking solenoid whereof the core is attracted each time a vehicle leaves said block section, a toothed wheel, racks meshing with said toothed wheel, rocking beams acting upon said racks, connections between said cores and said rocking beams, a support carrying said toothed wheel, slideable between said racks, a series of progressively numbered electric lamps, circuits supplying current to said lamps, a distributor controlling the supply circuits of said lamps, means for energizing said solenoids, whereby each time a vehicle enters or leaves said block section, said support is actuated by the corresponding solenoid core to operate said distributor in such a manner as to light up or extinguish the lamp showing the number of the vehicles in said block section.

3. In automatic block apparatus for electric tramways and railways, the combination of a blocking solenoid, whereof the core is attracted each time a vehicle enters the block section, a de-blocking solenoid whereof the core is attracted each time a vehicle leaves said block section, a toothed wheel, racks meshing with said toothed wheel, rocking beams acting upon said racks, connections between said cores and said rocking beams, a support carrying said toothed wheel, slideable between said racks, a series of progressively numbered electric lamps, circuits supplying current to said lamps, a distributor controlling the supply circuits of said lamps, means for energizing said solenoids, whereby each time a vehicle enters or leaves said block section, said support is actuated by the corresponding solenoid core to operate said distributor in such a manner as to light up or extinguish the lamp showing the number of the vehicles in said block section, said toothed wheel being so constructed and mounted that on a vehicle entering said block section at the same instant as a vehicle is leaving said block section, said toothed wheel will revolve idly without affecting said support, and no signal will be given.

In testimony whereof I have signed my name to this specification.

DINO SAMAIA.
